UNITED STATES PATENT OFFICE.

WILLIAM A. HASTINGS, OF LA GRANGE, ILLINOIS, ASSIGNOR TO ALUMINUM PRODUCTS COMPANY, OF LA GRANGE, ILLINOIS, A CORPORATION OF ILLINOIS.

DESIGN FOR A POT OR SIMILAR ARTICLE.

Application filed May 21, 1926. Serial No. 17,802. Term of patent 14 years.

To all whom it may concern:

Be it known that I, WILLIAM A. HASTINGS, a citizen of the United States, residing at 121 South Eighth Avenue, La Grange, Cook County, Illinois, have invented a new, original, and ornamental Design for a Pot or Similar Article, of which the following is a specification, reference being had to the accompanying drawing, forming part thereof.

The figure is a side elevation of the article showing my new design.

I claim:

The ornamental design for a pot or similar article, as shown.

WILLIAM A. HASTINGS.
